Inventor:

R. M. Marchant, Jr.

United States Patent Office.

ROBERT M. MARCHANT, OF WELLINGTON, NEW ZEALAND.

Letters Patent No. 80,417, dated July 28, 1868.

IMPROVED RAILROAD-RAIL.

The Schedule referred to in these Letters Patent and making part of the same.

TO ALL WHOM IT MAY CONCERN:

Be it known that I, ROBERT M. MARCHANT, of Wellington, New Zealand, have invented a new and improved Compound Rail; and I do hereby declare that the following is a full, clear, and exact description of the construction and operation of the same, reference being had to the accompanying drawings, making a part of this specification, in which—

Figures 1 and 2 are transverse sections.

This invention contemplates the combination of steel or wrought iron with cast iron and timber, (see fig. 1,) or with cast iron wholly, (see fig. 2,) for the construction of a uniformly-continuous rail, in which rail the portion subjected to wear shall be of steel or wrought iron, and the continuous seat for this portion of the rail shall be of cast iron, either on a substructure of timber, as per fig. 1, or on a longitudinal entirely of cast iron, as per fig. 2, the whole being securely united together by screw-bolts, which are to be screwed into and set up in the steel or wrought-iron portion of the rail itself.

The rail, constructed as per fig. 1, may be keyed on the ordinary sleepers by wooden keys, or otherwise secured, as may be desired.

The rail, constructed as per fig. 2, will only require such support under exceptional circumstances.

The weight of metal and size of rail will depend on the character of the traffic to which it is subjected.

For the application of Bessemer steel as the wearing portion, where the traffic is great and renewals frequent, the advantages offered by this rail, in either of the forms shown in figs. 1 and 2, are evident.

To enable any one skilled in the art to make and use my invention, I will proceed to describe its construction and operation.

A represents a rail of Bessemer steel or wrought iron, in twelve-foot or other convenient lengths, attached to a substructure of cast-iron seat and timber longitudinally by three-quarter-inch screw-bolts, two feet apart, except at the joints, where the attachment is made by two three-quarter-inch screw-bolts, one and seven-eighths of an inch from centre to centre of screw-bolt.

B represents cast-iron seat of rail in four-feet lengths, or other sub-multiple of A, having two slots of three and a half inches long, each slot, and two feet apart from centre to centre of slot, for free transmission of screw-bolts to rail.

C represents wrought-iron screw-bolts, screwing into A, and two feet apart from centre to centre, except at joints, where these bolts are one and seven-eighths of an inch from centre to centre of bolt.

D represents timber, doweled at joints, and in twelve-feet lengths, being bored for passage of three-quarter-inch bolts at joints of rail A, and elsewhere two feet apart.

E represents the position and size of dowel at joints of D, F washer under head of C, and g groove in continuous casting B, to be packed at joints.

A, in fig. 2, represents the same kind of rail as in the figure above, but in sixteen-feet or other convenient lengths, attached to the cast-iron longitudinal by three-quarter-inch screw-bolts, two feet apart, except at the joints, where the attachment is made by two three-quarter-inch screw-bolts one and seven-eighths of an inch from centre to centre of screw-bolt.

H represents a cast-iron longitudinal seating-rail A, in eight-feet lengths, or other sub-multiple of A, having four slots of three inches long each slot, and two feet apart from centre to centre, for free transmission of screw-bolts to rail.

The outer line shows the bellying of the casting at these slots.

I represents shoe-forming junction at joints of H.

Having thus fully described my invention, what I claim therein as new, and desire to secure by Letters Patent, is—

In the construction of railways, the arrangement of the rails A, with a continuous substructure, B or H, either with or without the wooden foundation D or iron plates I, the whole secured or bolted together, in the manner and for the purpose herein shown and described.

As evidence that I claim the foregoing, I have hereunto set my hand in the presence of two witnesses.

R. M. MARCHANT.
